UNITED STATES PATENT OFFICE

HENRY THOMAS, OF BARKING, ESSEX, ENGLAND, ASSIGNOR TO U. S. SLICING MACHINE COMPANY, OF LA PORTE, INDIANA, A CORPORATION OF INDIANA

LAST-SLICE HOLDER OR SUPPORT FOR SLICING MACHINES

Application filed December 15, 1925, Serial No. 75,629, and in Great Britain December 22, 1924.

Renewed August 3, 1929.

This invention relates to so called "last slice holders or supports" for slicing machines, the holders or supports being of the type comprising a number of rods or bars (with curved hooks or prongs thereon) rotatably mounted in a frame and adapted to be turned simultaneously, to project the hooks or prongs forward, through the medium of toothed wheels or segments fixed 10 on the rods or bars at one end of the frame.

In supports or holders of this type the prong-bars have generally been geared together by the toothed wheels or segments and operated collectively and simultaneously by turning a lever fixed on one of the bars.

With such a construction it sometimes happens that when the lever is actuated some of the prong-bars, owing to unavoidable backlash in the gear train, will not be turned to the full extent and the curved prongs thereon will then project further than they should. Consequently, when the last slice is being cut these prongs are apt 20 to foul the knife and cause damage.

According to the present invention this disadvantage is overcome by providing operating mechanism so constructed and arranged that the turning effort instead of being applied collectively to all the prong-bars is applied separately to each individual prong-bar or to each individual pair of prong-bars. The operating mechanism may comprise slidable means which may consist 30 of one or more slidable members, whereby the turning effort is applied separately to each individual toothed segment or wheel or to each individual pair of toothed segments or wheels.

The operating mechanism may comprise a single slidable toothed rack adapted to engage said segments or wheels or the toothed segments or wheels on adjacent prong-bars may be arranged out of alignment thus forming two rows and in this case the operating mechanism may comprise two slidable toothed racks, one of which engages all the toothed segments or wheels in one row and the other the segments or wheels in the other row, means being pro-

vided for sliding said racks simultaneously in opposite directions whereby the adjacent prong-bars are rotated in opposite directions. In order to obtain this result, instead of arranging the toothed segments or wheels on alternate prong-bars out of alignment, the toothed segment or wheel on one of the prong-bars may be wider than that on the other prong-bar but meshing therewith and the operating mechanism may comprise a 55 single slidable toothed rack adapted to engage the wider segment or wheel only. In this embodiment the toothed segments are arranged in pairs, the segments of each pair meshing with one another. In all cases the 60 operating mechanism is, or may be, so constructed and arranged that the prong-bars will be locked automatically against movement in the operative or inoperative position except by the actuation of said mechanism.

Various constructional embodiments of my present invention are illustrated, by way of example, on the annexed drawings, whereon:—

Fig. 1 shows one constructional form applied to a last slice holder described and claimed in the specification of my co-pending patent application Serial No. 75,628, filed December 15, 1925, for work-piece 80 holder for slicing machines.

Fig. 2 is a top plan view corresponding to Fig. 1;

Fig. 3 is a section on the line 2—2 in Fig. 1;

Fig. 4 is a fragmentary sectional elevation of one of the side members of a last slice holder frame and shows an arrangement of toothed wheels for use when adjacent prong-bars are to be rotated in opposite directions;

Fig. 5 is a fragmentary end elevation corresponding to Fig. 4 and also shows the rack member for operating the toothed wheels;

Fig. 6 is a fragmentary elevation of an arrangement of toothed wheels corresponding to that in Figs. 4 and 5 and illustrates one method of actuating the rack member;

Fig. 7 is a fragmentary view of the back 100

face of a cover plate wherein said rack member is slidably guided;

Fig. 8 is a fragmentary sectional end elevation corresponding to Fig. 6;

5 Fig. 9 is a top plan view corresponding to Fig. 6;

Fig. 10 shows modified operating mechanism applied to a last slice holder which is also described and claimed in my above mentioned specification.

10 Fig. 11 is a top plan view, partly in section, corresponding to Fig. 10;

Fig. 12 is a section on the line 12—12 in Fig. 10;

15 Fig. 13 is a fragmentary elevation of further modified mechanism for operating adjacent prong-bars in opposite directions;

Fig. 14 is a section on the line 14—14 in Fig. 13;

20 Fig. 15 is a top plan view, partly in section, corresponding to Fig. 14;

Fig. 16 is a fragmentary elevation of a still further modification;

25 Fig. 17 is a section on the line 17—17 in Fig. 16;

Fig. 18 is a top plan view, partly in section, corresponding to Fig. 16; and

30 Fig. 19 is a fragmentary view of a modified form of operating mechanism for two toothed rack members.

Referring to Figs. 1 to 3:—

The last slice holder illustrated is fully described in the specification of my co-pending patent application Serial No. 75,628 and 35 it is sufficient, for the purpose of the present description, to state that said last slice holder comprises prong-bars 1, of angle section, rotatably mounted in the side members 2 and 3 of the frame, said bars comprising prongs 4 which are adapted, when the prong-bars are 40 rotated in unison, to be projected into the substance held against the flat surface constituted by the vertical flanges of the prong-bars, see Fig. 3.

45 A rack member 5, formed on one edge with rack teeth 6, is slidably arranged at the back of the side member 3 of the frame, being guided thereon by means of pins 7 and 8 screwed into the member 3 and engaging in 50 elongated slots 9 and 10 formed in the rack member. Tooothed segments 11 are secured to the prong-bars 1, which latter are so spaced that the toothed segments do not mesh with each other. All the toothed segments are, 55 however, in mesh with the teeth 6 on the rack member 5 and the latter is operated by a lever 12 pivoted to said member by a pin 13 and having an elongated slot 14 in which the pin 8 is engaged. The slot 14 is also formed with 60 a portion 15 wherein the pin 8 engages when the lever 12 is in its normal position, in which position the prongs 4 are inoperative, as indicated in Fig. 3.

When the operating lever 12 is depressed, 65 the co-action of the pin 8 and the slot 14 in

said lever causes the rack member 5 to slide downwards and the prong-bars to be rotated in unison, and in the same direction, by reason of the engagement of the rack teeth 6 with the toothed segments 11, the prongs 4 being projected forwards towards the front of the last slice holder. Thus, the force applied to the lever 12 is also applied through the rack teeth 6 to each toothed segment 11 independently and backlash is reduced to a minimum being limited in respect to any one bar to the backlash between the toothed segments thereon and the rack teeth.

When it is desired to rotate adjacent prong-bars 1 in opposite directions so as to project the prongs 4 thereon in opposite directions, said bars may be provided with toothed wheels, or segments, constructed and arranged as illustrated in Figs. 4 and 5. It will be seen that the toothed wheel 16 on the topmost prong-bar 1 is wider than the toothed wheel 17 which meshes with said wheel and is mounted on the next adjacent prong-bar and that the toothed wheel 17 does not mesh with the wider toothed wheel 18 immediately below it. The wheel 18 engages with a toothed wheel 19 disposed in line with, and of the same width as, the toothed wheel 17. The prong-bars 1 are rotated in unison by means of a single rack member 20, formed with rack teeth 21 and arranged for sliding movement on the side member 3 of the frame of the last slice holder, so that said teeth only engage with the alternate toothed wheels 16 and 18, the width of the rack member 20 being substantially equal to the difference between the widths of the narrow and wide toothed wheels. In this way, the force applied to the rack member is applied to the wider toothed wheels 16 or 18 of the two pairs of adjacent toothed wheels 16 and 17 and 18 and 19 independently and it will be obvious that the toothed wheels 17 and 19 rotate in opposite directions to the wheels meshing therewith.

One form of mechanism for operating the rack member 20 is illustrated on Figs. 6 to 9, the rack member being slidably arranged in a guideway 22 which is formed in a cover plate 23 secured to the side member 3 of the frame. An operating lever 24 is pivoted, by means of a pin 25, to said cover plate and passes through an elongated aperture 26 formed in the back thereof and engages in a slot 27 formed in the back of the rack member 20. The pivotal movement of the operating lever 24 up or down will cause the toothed wheels 16 and 18, with which the rack member engages, to be rotated in one direction, the toothed wheels 17 and 19 meshing with the wheels 16 and 18 being rotated in the opposite direction, as aforesaid.

The prong-bars 1 in the construction illustrated in Figs. 10 and 12 are mounted for rotation in the frame of the last slice holder

in the manner described with reference to the construction in Figs. 1 to 3, but, in this case, the prongs 4 on two adjacent prong-bars are projected into operative positions in opposite directions, see Fig. 12. In order to cause the two adjacent prong-bars to rotate in opposite directions two rack members 28 and 29 are employed and the toothed segment 11 on one prong-bar is arranged out of alignment with the toothed segment 11 on the next adjacent bar, so that two separate rows of toothed segments are thus formed. The inner rack member 28 is slidably arranged on the back of the side member 3 of the frame and is formed with elongated slots 30 and 31, the outer rack member 29 being slidably arranged on the back of the rack member 28. The two rack members are held against movement away from the side member 3 by means of pins 32 and 33 screwed into said side member and passing through elongated slots 34 and 35 in the outer rack member and the slots 30 and 31 in the inner rack member. The rack member 28 is formed with a set of rack teeth 36 meshing with one of the rows of toothed segments 11 and the rack member 29 is formed with rack teeth 37 meshing with the other row of toothed segments 11. The operating lever 12 in this construction is pivoted, by means of a pin 38, to the outer rack member and is also formed with an elongated slot 14 engaged by the pin 33 whereby, when said lever is operated, the outer rack member is caused to move upwards or downwards as the case may be. The inner rack member would, however, remain stationary and in order to cause it to move simultaneously with the outer rack member a toothed pinion 39 is rotatably mounted on a pin 40 screwed into the side member 3 of the frame, said pinion being accommodated in an elongated slot 41 in the inner rack member while the head of the pin 40 is arranged in an elongated slot 42 in the inside of the outer rack member. The inner rack member is provided with teeth 43 engaging one side of the pinion 39, the other side of the latter being engaged by teeth 44 formed on the outer rack member. Thus, as the outer rack member is moved upwards or downwards, as the case may be, the engagement of the pinion 39 with the two sets of teeth 43 and 44 causes the inner rack member 28 to move in the opposite direction to the rack member 29, the adjacent prong-bars 1 and prongs 4 thereon also moving in opposite directions.

A modified form of mechanism for rotating two adjacent prong-bars 1 in opposite directions is illustrated in Figs. 13, 14 and 15. The toothed segments 11 are arranged in two separate rows as described above and a rack member 28 and 29 is provided for operating each row of toothed segments. The two rack members are disposed beneath a cover plate

45 secured to the back of the side member 3 of the last slice holder frame by means of screws 46 and 47. A shaft 48 is rotatably mounted in the cover plate 45 and in the side member 3 of the frame, said shaft having mounted thereon, at the exterior of said cover plate, an operating lever 49. Eccentric sheaves 50 and 51 disposed in diametrically opposite directions are secured to the shaft 48, a strap 52 being rotatably mounted on the sheave 50 and a similar strap 53 rotatably mounted on the sheave 51. The eccentric sheave 50 and co-operating strap 52 are arranged in a recess 54 formed in the back of the rack member 28 said member being also apertured at 55 so as to allow the shaft 48 to pass therethrough. The rack member 29 is also apertured at 56 for the same purpose and the eccentric sheave 51 and strap 53 are disposed in a recess 57 formed in said rack member. The eccentric straps 52 and 53 are connected, respectively, to the inner rack 28 and outer rack 29 by means of pins 58 and 59. When the operating lever 49 is turned the two rack members 28 and 29 will be slid in opposite directions because of the relative dispositions of the eccentric sheaves 50 and 51 on the shaft 48 and alternate prong-bars 1 will also be rotated in opposite directions because of the engagement of the rack teeth 36 on the rack member 29 and the rack teeth 37 on the rack member 28 with the two independent rows of toothed segments 11.

Referring now to Figs. 16 to 18, the modified mechanism for operating the two racks 28 and 29 illustrated in said figures comprises an operating lever 60 formed with two elongated cam slots 61 and 62. The two racks are held against movement away from the side member 3 of the frame of the last slice holder by means of two pins 63 and 64, which pass through slots 65 and 66 in the inner rack member 28 and slots 67 and 68 in the outer rack member. The operating lever 60 is secured to a member 69 which is rotatably mounted on a pin 70 screwed into the side member 3, a pin 71, engaging in the cam slot 61, being secured to the outer rack 29 and a pin 72, engaging in the cam slot 62, being also secured to the inner rack 28. The last mentioned pin passes through a slot 73 formed in the outer rack. It will be obvious that when the operating lever 60 is turned the two racks will be slid in opposite directions by reason of the co-action of the pins 71 and 72 with the cam slots 61 and 62 in said lever whereupon the adjacent prong-bars 1 will be rotated in opposite directions as already described above.

In Fig. 19 there is illustrated a still further modification of mechanism for rotating adjacent prong-bars in opposite directions. This mechanism corresponds to that illustrated in Figs. 10 to 12 but the pinion 39 for transmitting the movement of the outer rack mem-

ber 29 to the inner rack member 28, so that the latter is slid in the opposite direction, is not shown in Fig. 19. The two constructions differ, however, in that the operating lever 12, which is also pivoted on the outer rack member, is disposed in the opposite direction to the lever 12 of the construction in Figs. 10 to 12 with its cam slot 14 engaging the upper pin 32 instead of the lower pin 33.

10 In all the constructions described the arrangement of the slot (or slots) in the operating lever and pin (or pins) in the rack (or racks) is such that the prong-bars are automatically locked against movement in either direction except when moved by means of the operating lever.

15 Having now fully described my invention what I claim and desire to secure by Letters Patent is:—

20 1. In a last slice holder for slicing machines, a frame, a plurality of combined abutment and impaling members mounted in pairs in said frame, pinions on the respective members, pinions on each of a pair of the members meshing with one another, and an actuating rack meshing with one of the pinions on each of a pair of members for moving the members into and out of engagement with the material to be sliced.

25 2. In a last slice holder for slicing machines, a plurality of impaling means, a gear associated with each of a plurality of said impaling means, a rack meshing with a plurality of said gears and operative driving connection between said plurality of gears and the remaining gears, said gears being disposed in a plane transverse to the plane of said last slice holder.

30 3. In a last slice holder for slicing machines, a frame, a plurality of impaling means journaled in said frame, a gear associated with each of a plurality of said impaling means, a rack meshing with a plurality of said gears and operative driving connection between said plurality of gears and the remaining gears, said gears being disposed in a plane transverse to the plane of said frame.

35 4. In a last slice holder for slicing machines, rotatably mounted bars carrying impaling elements arranged along the length of said bars, a plurality of said bars each having a gear rigid therewith, and a rack meshing with some of said gears for rotating said bars, the remaining gears being driven by said rack driven gears.

40 5. In a last slice holder for slicing machines, a frame, a plurality of bars rotatably mounted in opposite ends of said frame, impaling elements carried by said bars, a gear on each of said bars, a rack meshing with some of said gears for rotating said bars, and operative driving connections for driving the remaining gears when said first mentioned gears are rotated.

45 6. In a last slice holder for slicing ma-

chines, a frame, longitudinally extending members journaled in the sides of said frame, impaling elements on said members, a plurality of said members each having a gear thereon, and means meshing with each of said gears for rotating said members.

50 7. In a last slice holder for slicing machines, a plurality of impaling members arranged in pairs, a narrow gear on one of said members of each pair meshing with a wide gear on the other member of each pair, and a rack disposed at one side of said narrow gears and meshing with a plurality of said wide gears.

55 8. A last slice holder comprising a plurality of rotatable members rotatably mounted in a frame, impaling elements on each of said rotatable members, gears operatively connected to each of said rotatable members for rotating said rotatable members, said gears having their centers substantially in line with each other, said gears being of substantially equal diameter, and a rack meshing with portions of alternate gears which project outside of the plane of the remaining gears, said remaining gears meshing with certain of said gears which are in mesh with said rack.

60 In testimony whereof I affix my signature.

HENRY THOMAS.
